CLAIM

The ornamental design for a smart network camera, as shown and described.

DESCRIPTION

FIG. 1 is a top, front and right side perspective view of a smart network camera showing our new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and right side perspective view thereof, shown in a disassembled state;

FIG. 10 is a top, rear, and right side perspective view thereof, shown in a disassembled state; and,

FIG. 11 is an enlarged portion view taken from encircled portion labeled, “FIG. 11,” in FIG. 1.

The dashed-dot-dot-dashed lines form the boundary of the enlarged portion views of FIGS. 1 and 11 and form no part of the claimed design. The dashed-dot lines show the boundary of the claim and form no part of the claimed design. The even dashed broken lines shown in the drawings are included for the purpose of illustrating portions of the smart network camera that form no part of the claimed design.
